UNITED STATES PATENT OFFICE

2,479,472

COMBINED SPECTACLE, MEMORANDUM,
AND ACCESSORIES CASE

Sherman S. Coplon, Kenmore, N. Y.

Application August 7, 1945, Serial No. 609,376

5 Claims. (Cl. 150—35)

1

This invention relates to a combined spectacle case and article holder.

Salesmen compelled to wear spectacles, particularly retail salesmen in furniture, clothing, and other stores selling large articles to be delivered and requiring notations respecting places and dates of delivery and/or other memoranda, find it necessary, under ordinary conditions, to withdraw their spectacle cases from their pockets, remove the spectacles therefrom and return the cases to their pockets, and then remove their pencils from the same or other pockets and finally take out their memorandum pads from a third pocket, each under separate action or movement. Oftentimes, due to failure of a salesman to return the several articles to their proper places in his garment, confusion occurs when use of the device is again required and loss of time necessarily results from such action.

Housekeepers and others, in many instances, require the use of spectacles and on occasions jot down many items to be purchased on a shopping tour, with the result that on entering a car or bus they open their handbags, seeking the proper coin, token or ticket for transportation. On reaching their destinations it is common to find that they resort to their list of articles to be purchased, which again necessitates the use of their spectacles, reached for separately in the handbags; reviewing their notations of the items to be purchased is next in order and finally a pencil is looked for among the many articles carried in the hand bag in order to check the items as they are purchased, all of which results in inconvenience, lost motions, delay and occasionally confusion.

It is the object of my invention to provide a combined spectacle case and article holder embodying a pocket for the spectacles, a pocket for coins, tokens or transportation tickets, a pencil sleeve or retainer and a memorandum pad, all conveniently assembled so that when removing the device from a pocket or hand bag, all of such articles are conveniently accessible.

Another object of my invention is to provide a device of the kind mentioned which is simple in construction, inexpensive, and whereby in grasping the device in one hand, the spectacles and other articles may be successively removed as needed, notations made or deleted and the various articles used quickly returned to their places in the device, all to be returned in assembled condition to one's pocket or hand bag for future use.

In the accompanying drawings I have illustrated my invention in two forms falling within

10 the scope of the appended claims, whereby spectacles are properly protected, a pencil conveniently retained in a manner to guard against breakage of its point and wherein a memorandum pad or means to enter notations is quickly presented upon opening the case or cover, and coins, tokens or the like conveniently carried so that they are easily accessible; all securely retained in their respective places by retainer flaps or covers cooperating with such parts.

15 In the drawings:

Fig. 1 is a perspective view of one form of my device shown in closed condition.

15 Fig. 2 is a perspective view of the form of device shown in Fig. 1, showing the same open to quickly enable the spectacles to be withdrawn from its pocket, the pencil from its sleeve or retainer, and the memorandum pad in position to make notations or delete notations thereon and wherein 20 upon lifting the pad, the coin pocket will be easily accessible.

25 Fig. 3 is a view similar to Fig. 2, with the main closure flap broken away, the spectacles removed from its pocket, the pencil from its sleeve or retainer and the memorandum pad removed so as to illustrate the closure flap provided for the coin pocket.

30 Fig. 4 is a longitudinal section taken on or about line 4—4, Fig. 1, looking in the direction of the arrow crossing said line.

35 Fig. 5 is a longitudinal section taken on line 5—5, Fig. 4, looking in the direction of the arrow crossing said line.

Fig. 6 is a longitudinal section taken on line 6—6, Fig. 1, looking in the direction of the arrow crossing said line.

Fig. 7 is an enlarged cross section taken on line 7—7, Fig. 4.

Fig. 8 is an enlarged cross section taken on line 40 8—8, Fig. 4.

Fig. 9 is a perspective view of a modification of the device shown in Fig. 1, the device being illustrated in closed position.

45 Fig. 10 is a perspective view of the modified form of my device, showing the same open.

Fig. 11 is a sectional perspective view of the lower portion of the device, showing the spring expander in section within the spectacle pocket, the closure flap for the coin pocket in open position and the extended closure flap closing the front of the device broken away.

Fig. 12 is a vertical section taken on line 12—12, Fig. 9.

Fig. 13 is a broken perspective view of the spring expander whereby the desired shape of the spec-

tacle pocket is established and the pencil pocket formed within the spectacle pocket.

Fig. 14 is a transverse section taken on line 14—14, Fig. 9.

Fig. 15 is a vertical section taken through a portion of the length of the spectacle pocket, on line 15—15, Fig. 14.

Fig. 16 is a transverse section taken on line 16—16, Fig. 9.

The exemplification of my device shown in Figs. 1 to 8 inclusive, is in the form of a case constructed of flexible leather or other suitable material and it comprises a comparatively flat rear member or strip 11 and a front member or strip 12, somewhat wider than said rear member, stitched along its longitudinal marginal portions to the longitudinal marginal portions of the rear member, as at 13; the front member having a fullness transversely because of its increased width along at least a portion of its length, to enable it to be spaced from the rear member so as to form a pocket 14 for spectacles designated by the numeral 15. The front member is also stitched longitudinally to the rear member inwardly from one margin, as at 16, so that the fullness provided for the front member will form a pencil sleeve or retainer 17. In order to hold the front and rear members separated throughout the width of the pocket 14, a spring U-shaped expander 18 of the usual type is inserted in the pocket.

The front member 12 is extended downwardly a considerable distance beyond the lower end of the rear member 11 to form a closure flap 19 and this front member is folded and stitched at the fold to the rear member along the lower marginal portion of the latter, as at 20, so as to form an outwardly-directed folded portion which closes the lower end of the pocket 14. The stitching 20 may be a continuation of the stitching 13 along the longitudinal marginal portions of the two members and it is continued along the entire length of the pencil shield or retainer 17, which latter preferably terminates at its lower end in line with the lower end of the pocket 14 and at its upper end a short distance below the upper end of said pocket, so that the blunt end of the pencil, designated by the numeral 21, which may be rubber tipped or otherwise, projects from the shield or retainer and can be easily removed. It is to be noted that the rear member 11 of the case extends a distance beyond the upper end of the front member 12 to form a retainer and closure flap 22, preferably somewhat shorter than the closure flap 19, which also serves as a retainer for certain parts of the case or device, as will appear hereinafter.

The closure flap 19 has a leather or other flexible frame-like element 23 secured to its inner side. This frame-like element is stitched along the longitudinal marginal portions of the flap 19, as at 24, and also along the outer or free end of the latter, and it also has a certain degree of fullness to enable a calendar, a Celluloid or other transparent sheet and business cards to be inserted behind the same, it being provided with an opening 25 through which the calendar can be seen. By reason of this frame-like element being stitched in the manner stated, it serves as a card pocket, under which term any card-like element including the Celluloid facing sheet may be included, the pocket being open at its upper end when the flap 19 depends from the lower end of the remainder of the case; but when said flap is closed, the opening of the card pocket will be

closed by the folded portion of the flap and any card or other similar articles, even though loose in the pocket, will be retained therein. Therefore, when the case is opened in the manner shown in Fig. 2, the opening to the pocket 14 for the spectacles and the opening for the card pocket on the flap 19 are at the upper ends of said pockets. The opening to the pencil shield or retainer is also at the upper end of the latter so that by grasping the device with one hand at the region between the flaps 22 and 19, the spectacles, pencil and cards are conveniently accessible.

Near the upper end of the pocket 14, the front member 12 is slit transversely, as at 26, 27, the slits being spaced apart and the material between the slits serves as a pad retainer of a type such as illustrated at 28 in the drawings. The pad comprises a cardboard or other similar backing 29 which is passed through the upper slit 26 from the outside and thence through the lower slit 27 from the inner side of the front wall 12 of the pocket 14, said backing having the various sheets 30 forming the pad glued or otherwise secured to its upper end. This means for positioning the memorandum pad against the front of the pocket 14 may be modified, since there are various ways in which this can be accomplished without departing from my invention. In any event, the pad is removably applied to the front of the pocket 14 and since the spring-like expander 18 serves to expand said pocket, a substantially rigid backing is provided for the memorandum pad, which, when the device is placed in the palm of one hand, enables the user to conveniently make notations on the pad or erase or delete any notations thereon. The flap 19 cooperates with said memorandum pad, in that the pressure of the flap applied to the pad when the case is in one's pocket, will prevent the pad being accidentally forced from its retainer, and at the same time the flap will conserve any notations made on the pad and keep the latter clean.

The front wall of the pocket 14 is provided with a coin or ticket slit 31, which preferably trends longitudinally and opens into a coin pocket 32 formed of twill or other suitable material stitched, as at 33, or otherwise secured to the inner surface of the front wall 12, or otherwise fastened thereto, the slit 31 opening into said pocket 32, as clearly shown in Fig. 8.

When the coin pocket 32 has coins, tokens or transportation tickets placed therein, it extends into the pocket 14 provided for spectacles. The location of the coin pocket is such that the major portion thereof lies in the region of the bridge or nose piece of the spectacles and, therefore, no difficulty is experienced in inserting the spectacles into its pocket, particularly since the lense portions of the spectacles may be placed against the rear member 11 of the case while the temples lie outside of the region occupied by the coin pocket. In order to seal the coin pocket and prevent accidental loss of the coins or other articles therein, the rear member 11 of the case has extending laterally from one of its longitudinal edges a closure flap 34 which is folded forwardly and inwardly against the front of the pocket 14, thus completely overlying the region of the coin pocket and closing the coin or ticket slit 31 thereof. This closure flap 34 preferably extends across or approximately across the entire width of the pocket 14 and is placed behind a retainer loop 35 formed by slitting the front wall of the pocket 14 vertically with the slits thereof in spaced relation, and forcing the material be-

tween the slits outwardly to form the retainer loop, as best shown in Figs. 3 and 8. It is to be noted that the flap 19 also overlies the closure flap 34 and thus keeps the latter within the retainer loop, particularly when the case is pocketed and pressure is applied to the flap 19.

It will be apparent, therefore, from the foregoing that spectacles, pen or pencil, a memorandum pad and coins are easily accessible so that an individual accustomed to wearing glasses need only remove the case from a pocket or hand bag and find all accessories easily accessible for making notations and having coins or the like conveniently at hand for paying fares, etc. Both the rear member 11 and the front member have portions which fold over the various pockets and memorandum pad, the front member folding upwardly upon itself, as at 36, so that the folded portion or closure flap 19 lies against the memorandum pad and protects as well as aids in keeping the same in place, and also keeps the closure flap 35 of the coin pocket in closing position, while the folded portion of the rear member or closure flap 22 extends downwardly from its folding region 37 and overlies the upper portion of the closure flap 19 to hold the latter closed. Thus, when inserting the case into the breast pocket of a coat or into a vest pocket, the folded closure flap 19 remains in closed position, and if the depth of the pocket permits, the closure flap 22 also lies against the front wall of the pocket. This flap remains in a depending position and covers both the spectacles and the pencil or pen. If desired, the flap 22 may be fastened to the flap 19 in any well-known manner and while this might be of some slight advantage when the case is inserted in a hand bag, it usually is found unnecessary when the case is placed in a pocket.

If desired, the card pocket shown on the inner side of the closure flap 19 in Figs. 1 and 2 of the drawings may be omitted, and the case is shown in Figs. 4 to 8, without this card pocket.

In the modification shown in Figs. 9 to 16 inclusive, the rear member of the case is designated by the numeral 11^a and the front member by the numeral 12^a. The front member 12^a is considerably shorter than the rear member and it is stitched along its longitudinal marginal portions to a medial portion of the rear member so that end extensions 38 and 39, respectively, are provided at the upper and lower ends of said rear member, the upper end extension being somewhat shorter than the lower end extension.

The members 11^a and 12^a are spaced apart to form the spectacle pocket 14^a, the stitching 16 provided in the preceding figures, which divides the case into a spectacle pocket and a pencil pocket, being omitted. In this modification, however, I employ a stop strip 40, which spans the space between the front and rear members and has its ends stitched or otherwise secured to said members, as at 41. The spring expander 18 is inserted into the spectacle pocket and one leg 18^a bears against one edge wall of said pocket while the other leg 18^b bears against the stop strip 40 which is spaced a distance from the other edge wall of said pocket approximating the thickness of a pencil, as best shown in Fig. 14, so that a pencil sleeve or retainer 17^a is formed along one edge of the case.

The lower end extension 39 serves in part as a closure flap, and it is folded upwardly similar to the flap 19 in the previously described construction. A portion of this extension flap is

stitched to the case along its vertical marginal portions, as at 42, 43 and also fastened to the front member 12^a, as at 44; thus a coin or article pocket 32^a is formed at the lower end of the case, the front member 12^a of the case serving as the rear wall of said pocket while the region of the lower end extension 39 upwardly a distance from its fold 36^a serves as the front wall of said pocket. The said region of the lower end extension is provided with a coin slit 31^a and with a retainer loop 35^a, adapted to receive the end of a closure flap 34^a extending laterally from the rear member 11^a and adapted to be folded over the front of the coin or article pocket to close the coin slit 31^a. That portion of the lower end extension 39 above the fastening means 44 serving as a closure flap 19^a which may be folded to extend downwardly, as shown in Fig. 10, and thus expose the means provided to hold notation paper against the front of the spectacle pocket, and also to prevent the hand, while making notations on the pad, from coming in contact with said closure flap 34^a and working the same loose from its retainer loop 35^a.

In this modification I have shown a paper-slip retainer 45 formed of a strip of sheet aluminum or similar material to provide a flat rear member 46, having L-shaped forwardly extending flanges 47 along both vertical edges and an L-shaped flange 48 along its lower edge; thus forming an open pocket into which sheets or slips of paper 49 may be inserted from the upper end thereof and any desired notation made thereon. As these sheets or slips of paper are loosely held in the retainer so formed, the outermost sheet or slip, after the desired notation is made thereon, may be easily withdrawn and a clean sheet or slip exposed for making further memoranda. This retainer is riveted at its upper end to the front wall of the spectacle pocket, as shown at 50, Fig. 14.

The closure flap 19^a may be referred to as the loose portion of the lower end extension 39 of the rear member 11^a while the front wall of the coin or article pocket 32^a is the secured portion of said end extension. The fastening means 44 for securing the lower end extension to the front member 12^a is shown in part as stitches extending inwardly and upwardly from the side stitching 42 and 43 to staples 51 which are driven through the L-shaped flange 48 of the retainer 45. However, any other means for securing the lower end extension to the front member of the case to close the coin or article pocket 32^a at its upper end may be resorted to. It is to be noted that the closure flap 19^a serves to protect and keep the outermost sheet or slip of paper in the retainer 45 clean and when turned down to expose the paper, it will prevent loosening of the retainer flap 34^a, as previously stated.

It will be apparent from the foregoing that complete cooperation and dependence exists between the several parts of my improved case to function in the manner intended for them, and that each part has association with other parts to provide advantages not existing in devices of this kind.

Where in the claims the term "memorandum pad" is used, it is to be given a broad interpretation to include any element or object upon which notations or memoranda can be made.

Having thus described my invention what I claim is:

1. A case of the kind described having an upwardly-opening spectacle pocket with spaced-

apart front and rear walls, a coin pocket within said spectacle pocket fastened to the inner side of said front wall, said front wall having means of access to said coin pocket, a downwardly-closing flap extending from the rear wall of said spectacle pocket and normally closing the latter, and a closure flap extending from said last-mentioned wall and folded over the front wall of said spectacle pocket to cover the means of access to said coin pocket.

2. A case, formed of a strip of material folded transversely near one end to form a closure flap, a second strip of material folded approximately midway between its ends and at its folded portion being transversely fastened to and directed outwardly away from the opposite end of said first-mentioned strip, the portion of said second strip at one side of said outwardly-directed folded portion being fastened at its longitudinal edges to the longitudinal edges of the first-mentioned strip from said folded portion to said closure flap and adjacent one of said longitudinal edges and parallel thereto to form a spectacle pocket and a pencil pocket disposed one parallel to the other, the portion of said second strip at the opposite side of its folded portion being free and foldable upwardly over the fastened portion of said second strip and adapted to have said closure flap overlap said free foldable portion, the outwardly-directed folded portion of said second strip forming the bottom of said spectacle pocket.

3. A case, formed of a strip of material folded transversely near one end to form a closure flap, a second strip of material folded approximately midway between its ends and at its folded portion being transversely fastened to and directed outwardly away from the opposite end of said first-mentioned strip, the portion of said second strip at one side of said outwardly folded portion being fastened at its longitudinal edges to the longitudinal edges of the first-mentioned strip from said folded portion to said closure flap and adjacent one of said longitudinal edges and parallel thereto to form a spectacle pocket and a pencil pocket disposed one parallel to the other, the portion of said second strip at the opposite side of its folded portion being free and foldable upwardly over the fastened portion of said second strip and adapted to have said closure flap overlap said free foldable portion, the outwardly-directed folded portion of said second strip forming the bottom of said spectacle pocket, and a U-shaped spring-expander inserted in said spectacle pocket to hold the second strip separated throughout the width of said pocket from said first-mentioned strip.

4. A case, formed of a strip of material folded transversely near one end to form a closure flap, a second strip of material folded approximately midway between its ends and at its folded portion being transversely fastened to and directed outwardly away from the opposite end of said first-mentioned strip, the portion of said second strip at one side of said outwardly folded portion being fastened at its longitudinal edges to the longitudinal edges of the first-mentioned

strip from said folded portion to said closure flap and adjacent one of said longitudinal edges and parallel thereto to form a spectacle pocket and a pencil pocket disposed one parallel to the other, the portion of said second strip at the opposite side of its folded portion being free and foldable upwardly over the fastened portion of said second strip and adapted to have said closure flap overlap said free foldable portion, the outwardly-directed folded portion of said second strip forming the bottom of said spectacle pocket, and a U-shaped spring-expanded inserted in said spectacle pocket to hold the second strip separated throughout the width of said pocket from said first-mentioned strip and to maintain the fastened folded portion of said second strip in a stretched and rigid manner, and an element carried by said stretched and rigid portion to enable notations to be made thereon when the free foldable portion of said second strip is unfolded.

5. A case, formed of a strip of material folded transversely near one end to form a closure flap, a second strip of material folded approximately midway between its ends and at its folded portion being transversely fastened to and directed outwardly away from the opposite end of said first-mentioned strip, the portion of said second strip at one side of said outwardly-directed folded portion being stitched along its longitudinal edges to the longitudinal edges of said first-mentioned strip from said folded portion to said closure flap and being further stitched in closely spaced relation to one of said longitudinal edges and parallel thereto to form a spectacle pocket and a pencil pocket disposed one parallel to the other, a coin pocket stitched to the inner side of said second strip within said spectacle pocket, said second strip having a slit therethrough opening into said coin pocket and said first-mentioned strip having a closure flap extending from one of its longitudinal edges and folded over the front of the fastened portion of said second strip to close said slit, the portion of said second strip at the opposite side of its folded portion being free and foldable upwardly over the stitched portion of said second strip and over said last-mentioned closure flap and adapted to have said first-mentioned closure flap overlap said free portion when folded, the outwardly-directed folded portion of said second strip forming the bottom of said spectacle pocket.
